UNITED STATES PATENT OFFICE

JOSEPH E. SWENDEMAN, OF BOSTON, MASSACHUSETTS

SPRAYING APPARATUS

Application filed December 17, 1923. Serial No. 681,305.

This invention relates to a novel and improved spraying apparatus, susceptible of general application, although, as herein shown, being especially useful in apparatus known as absorbers, wherein oil is sprayed upon natural gas to remove therefrom vapors of liquid such as gasoline and water. The sprayer is also useful in connection with installations wherein sprays of water are used in the condensation of steam.

The invention will be best understood by reference to the following description, when taken in connection with the accompanying drawings of one specific embodiment thereof, while its scope will be more particularly pointed out in the appended claims.

In the drawings:

Fig. 1 is a vertical, sectional view of a portion of an absorber equipped with a spraying apparatus exemplifying the invention; and

Fig. 2 is a sectional view on an enlarged scale on line 2-2 of Fig. 1.

Referring to the drawings, and to the embodiment of the invention which is selected for exemplification, there is shown in Fig. 1 a vertical shell or casing 3, into the bottom of which the natural gas may be admitted, a gas outlet pipe 4 being provided for the escape of the gas after being subjected to the action of the oil sprays. The casing is provided with a cover-plate 5, to which is attached an oil inlet conduit 6, having a portion 7 which depends within the chamber presented by the casing. The conduit presents one or more, herein a plurality of spray orifices 8, arranged in vertical series, and herein progressively decreasing in diameter toward the bottom. In practice, the combined capacity of the outlet orifices corresponds in a general way to the capacity of the principal portion of the conduit.

The characteristics of each of the individual spraying devices will now be described, reference being had to Fig. 2. Each spraying device presents a central passage 9, with which the outlet orifice 8 communicates by way of a chamber 10 about a central passage. This lateral chamber is conveniently formed within a lateral projecting, depending flange, or skirt, 11, conveniently

formed integrally with an internally threaded stem 12 and an externally threaded stem 13, as by a laterally extending web 14 connecting the latter stem with the skirt, and presenting a plurality of passages 15. In the present example, the internally threaded stem is larger in diameter than the externally threaded stem, thereby to facilitate carrying out the idea of connecting together a series of spraying devices progressively decreasing in size lengthwise of the series, as by the use of a series of intervening spacers or connecting devices 16, each internally threaded to receive the externally threaded stem on one spraying device, and externally threaded at its other end to enter the internally threaded stem on the next adjacent spraying device. The length of these spacers may be such as to suit the circumstances of the particular installation.

In the present example, the outlet orifice of each spraying device is adjustable in width, thereby to vary its capacity, and in the present example, this is conveniently accomplished by the provision of an axially adjustable collar or sleeve 17, presenting a laterally projecting flange 18, which is arranged for cooperation with the flange 11. Adjustment of this sleeve is conveniently accomplished by threading the same onto the externally threaded stem 13, on which the sleeve can be rotated in the proper direction to produce the desired adjustment. When this adjustment has been obtained, it may be preserved by utilizing the spacer 16 as a lock-nut screwed endwise against the sleeve. In the case of the lowermost sleeve of the series, there is provided an internally threaded cap 19, which closes that end of the conduit and is threaded onto the externally threaded stem 13, the cap in this case serving as a lock-nut for the adjustable sleeve of the adjacent spraying device.

In operation, when the spraying apparatus is used in connection with an absorber for natural gas, oil is supplied under pressure to the inlet of the conduit 6, and issues from the several orifices in the form of conical sprays in the directions indicated by the arrows in Fig. 1. The gas in passing in an upward di-

rection through the several sprays is freed of gasoline and oil vapors, which are then precipitated to the bottom of the apparatus, where suitable disposition is made of them, as by the use of a trap not shown herein, which discharges the liquid contents, without permitting the escape of gas.

Having thus described one embodiment of the invention, but without limiting myself thereto, what I claim and desire by Letters Patent to secure is:

1. In a spraying apparatus, a conduit having a central passage, a laterally disposed annular flange forming with said conduit an annular chamber, and another laterally disposed annular flange spaced from the first-mentioned flange closing said chamber and forming an orifice affording an outlet from said passage by way of said annular chamber, the last-mentioned flange being carried by a sleeve having screw-threaded engagement with said conduit for movement lengthwise thereof, said conduit including two parts having screw-threaded engagement with each other, and one of such parts engaging said sleeve endwise.

2. In a spraying apparatus, a conduit having a central passage, a laterally disposed flange forming with said conduit one or more lateral passages leading therefrom, and an outer sleeve forming with said flange an annular outlet orifice about said central passage, said sleeve being movable lengthwise of said conduit to vary the width of said outlet, another outer sleeve engaging the first-mentioned sleeve endwise, and an inner part having screw-threaded engagement with both of said sleeves.

In testimony whereof, I have signed my name to this specification.

JOSEPH E. SWENDEMAN.
